UNITED STATES PATENT OFFICE.

FRANK SCHAFFER, OF BARBERTON, OHIO, ASSIGNOR TO THE DIAMOND MATCH COMPANY, OF CHICAGO, ILLINOIS, A CORPORATION OF ILLINOIS.

MECHANICAL MOVEMENT.

1,203,913.

Specification of Letters Patent.

Patented Nov. 7, 1916.

Application filed May 4, 1914. Serial No. 836,109.

To all whom it may concern:

Be it known that I, FRANK SCHAFFER, a citizen of the United States, and resident of Barberton, in the county of Summit and 5 State of Ohio, have invented certain new and useful Improvements in Mechanical Movements, of which the following is a specification.

This invention relates to an improvement 10 in mechanical movements, having reference especially to means for converting continuous rotary into intermittent rotary motion and for positively locking the driven element during the intervals of rest, such as is 15 required for severing the cardboard as fed by the feed-rollers of match box-shuck making machines, and for other purposes.

The object of the invention is to provide a mechanical movement of the character mentioned which shall be simple and durable in 20 construction and uniform and positive in operation, and which shall be free from abrupt jarring blows during the starting moments.

25 My invention comprises rotary driving and driven elements, whereof the driving element is provided with a plurality of tappets and the driven element is provided with a plurality of radial channels having articulated entrance-portions which are coördinated with the tappets, as will be hereinafter described and claimed.

In the drawings—Figure 1 is a side elevation of a mechanical movement embodying 35 my invention, the same being represented as applied to feed-rollers, and the elements being illustrated in the relative positions which they occupy at the instant of locking the driven element. Fig. 2 is a side elevation 40 of the elements, showing the driving element slightly advanced while the driven element remains locked. Fig. 3 is a similar view showing the action of a tappet stud upon a channel of the driven element to 45 impel the latter. Fig. 4 is a plan of Fig. 2.

10 designates the continuously rotating driving element and 11 the intermittently rotatable driven element of my improved movement. In the present instance the two 50 elements are in the form of spur wheels, the driving element being in mesh with a driving pinion 12 and the driven element being in mesh with one of the pinions 13 of a pair of feed-rollers 14. The shafts of the two spur wheels are designated 15 and 16, respectively.

On the outer face of the wheel 11 are formed a plurality of radial channels 17 disposed successively at corresponding angles to each other. In the present instance there are four channels disposed at angles of 90° to each other. The walls of each channel are parallel to its radial center line, excepting at their outer ends which are flared or rounded as indicated at 18.

The wheel 10 is mounted laterally adjacent the channeled side of the wheel 11, and is provided on its inner face with a plurality of projecting tappets 19, comprising studs or rollers—in the present instance three. The tappets are equally spaced apart at 60 points equidistant from the center of the wheel 10, the spaced relation of the tappets to each other and to the radial channels of the wheel 11 being such that the tappets enter the said channels in successive order, 65 move along the same toward the center of the wheel and then recede therefrom, and that as the active tappet in a receding motion approaches the mouth of the channel with which it is engaged the succeeding tappet 70 enters the mouth of the next following channel, and so on.

The curvature of the outer ends of the channels is such that when the elements are in the relative positions represented in Figs. 1 and 2 the inner walls of the mouths of the two lower channels are concentric to the wheel 10, that is, such walls comprise corresponding arcs described from the center of the wheel. Hence when both tappets 75 register with and move on the proximate articulated portions of the channels no motion is transmitted from the continuously rotating driving to the driven element, but on the contrary the latter is temporarily locked 80 against rotation; yet the instant the rearward tappet escapes the mouth of the proximate channel the leading tappet contacts 85 with and rides upon the opposing radial wall of its channel, progressively entering the 90 latter, as seen in Fig. 3, and then receding 95 therefrom. The three tappets of the driving element during its continuous rotation thus act in successive order upon the walls 100 of the radial channels of the driven element 105 and thereby intermittently rotate the latter, and positively lock it during the intervals of rest.

Owing to the relation of the tappets of the driving element to the channels of the 110

driven element whereby two tappets co-act concurrently with the arcuated portions of two channels during each interval of rest, not only is an effective locking of the driven element insured but the abrupt starting blows inherent in an ordinary Geneva stop motion are avoided.

I claim—

Mechanism of the character described comprising two rotatable members mounted in lateral relation to each other, one of said members constituting a driven element having a series of corresponding radial channels with flaring arcuate portions at their outer ends, and the other member constituting a driving element having a series of tappets equally spaced apart at points equidistant from its center and adapted to co-act successively with the walls of the said

channels and impart to the driven element 20 an intermittent rotary motion, two of the said tappets concurrently contacting with and riding upon the adjacent arcuate portions of the two channels at the end of each impulse of the driven element, the walls of 25 said adjacent arcuate portions comprising corresponding arcs described from the center of the driving element with a radius equal to the radial distance of the inner face of the tappets from said center. 30

Signed at Barberton in the county of Summit and State of Ohio, this 29th day of April, A. D. 1914.

FRANK SCHAFER.
